F. L. BUTLER.
ELECTRIC FIXTURE.
APPLICATION FILED NOV. 12, 1920.

1,391,610.

Patented Sept. 20, 1921.

UNITED STATES PATENT OFFICE.

FRANK LOWELL BUTLER, OF CHICAGO, ILLINOIS.

ELECTRIC FIXTURE.

1,391,610.

Specification of Letters Patent. Patented Sept. 20, 1921.

Application filed November 12, 1920. Serial No. 423,636.

To all whom it may concern:

Be it known that I, FRANK L. BUTLER, a citizen of the United States, and a resident of Chicago, in the county of Cook and 5 State of Illinois, have invented a new and useful Improvement in Electric Fixtures, of which the following is a full, clear, and exact description.

My invention relates to improvement in 10 electrical fixtures, and it consists in the combinations, constructions, and arrangements herein described and claimed:

An object of my invention is to provide an improvement over the electric fixture 15 shown in my prior application for patent, filed Oct. 2, 1920, in which I disclosed an insulated stem comprising an insulating nipple having its upper end screwed into a coupling secured to a fixed support and carrying on its lower end a cap formed with a threaded central opening adapted to receive the threaded end of a rod that carries at its 20 lower end a member suitable for connection with and for supporting a lighting fixture element, said improvement consisting in the provision of an insulating member having a central bore adapted to receive an ordinary tubular member formed with a so-called "running thread" and having means for limiting 25 the movement of the tubular member within the insulating nipple and for maintaining the same in adjusted position therein.

A further object of my invention is to 30 provide a device of the type described that comprises elements that can be assembled quickly and easily, wherefore the device can be properly installed with a minimum of time and effort.

40 A further object of my invention is to provide a device of the type described in which the number of component elements is reduced to a minimum.

A further object of my invention is to 45 provide a device of the type described that is effective for the purpose intended and thoroughly practical commercially.

Other objects and advantages will appear in the following specification, and the 50 novel features of the invention will be particularly pointed out in the appended claims.

My invention is illustrated in the accompanying drawings, forming part of this application, in which—

55 Figure 1 is a central section through the

device showing the use and application thereof.

In carrying out my invention, I make use of a fixed support, such as a gas pipe 1 that depends from a ceiling 2. I provide a coupling 3 threaded interiorly at each end and formed with a transverse partition 4 intermediate its length. The coupling 3 is screwed on the threaded lower end of the gas pipe 1. A cylindrical insulating member 5 has its upper end threaded exteriorly at 6 for engagement with the coupling 3. A pin 7 projected through transverse registering openings 8 and 9 through the wall of the coupling 3 and the insulating member 5 adjacent its upper end, respectively, prevents movement of the insulating member relative to the coupling.

The insulating member 5 is formed with a central bore 10 threaded adjacent its lower 75 end to receive a threaded tube 11 having a so-called "running thread" 12 the entire length thereof. A pin 13 is projected through transverse openings 14 and 15 through the insulating member 5 adjacent 80 the lower end thereof and through the tube 11, respectively, thereby maintaining the tube 11 in a fixed adjusted position relative to the insulating member 5 and limiting the movement of the tube 11 upwardly in the 85 threaded bore 10. It is to be understood that the threaded tube 11 is of the conventional form, such as is commonly used in the installation and assembly of electric fixtures. The tube 11 is cut to a suitable 90 length and the upper end thereof is secured in the bore 10 in the manner described. A canopy 16 is then projected over the tube 11 until the upper end thereof abuts against the wall 2. A nut 17 screwing on the lower 95 end of the tube 11 supports and maintains the canopy 16 in position.

The canopy 16 is provided with a plurality of spaced apart openings 19 extending through its wall as shown, each being 100 adapted to receive the tubular shank 20 of an eye member 21. The latter are held in adjusted position relative to the canopy by nuts 22 screwing on the threaded portions of the tubular shanks 20 projecting within 105 the canopy, a shoulder 23 being provided on each shank exterior of the canopy casing. Chains 24 engaging with the eye members 21 may be operatively connected with a chandelier or other lighting fixture member 110

(none being shown) to support the latter. Electrical conducting wires 25 are projected into the canopy 19 through the bores of the tubular shanks 20 of the eye members 21 for engagement with the wires (not shown) that are ordinarily installed in the ceiling 2.

From the foregoing description of the various parts of the device, the operation thereof may be readily understood. The 10 device comprises relatively few parts and can therefore be assembled and installed with economy in time and labor. Since the insulating member 5 is adapted to receive an ordinary tube formed with a "running 15 thread", the length of the tube 11 may be varied as required in each particular installation, since a desired length of the tube 11 is cut from standard lengths of this element of the device.

20 It will be observed that the nut 17 is formed with a hollow cap portion 18 adapted to be grasped by hand to permit convenient operation of the nut and into which the lower end of the tubular member 11 may 25 extend, wherefore the length of the tubular member 11 may vary considerably without rendering the same unsuitable for the purpose intended.

I claim:

30 1. In an electric fixture of the character described, the combination of a fixed support, a cylindrical insulating member provided with a bore and having diametrically opposed openings extending through 35 its walls adjacent the lower end of the insulating member, means for connecting said fixed support and said insulating member, a tubular member threaded exteriorly and having its upper end inserted a predetermined distance into the bore of said insulating member, said second named tubular

member having diametrically opposed openings extending therethrough adjacent the upper end thereof, a pin projected through the openings in the walls of the insulating member and the openings through said second named tubular member to determine the position of the latter in said bore, and means carried by said second named tubular member for supporting a lighting fixture element. 45

2. In an electric fixture of the character described, the combination of a fixed support, a cylindrical insulating member provided with a bore and having diametrically 50 opposed openings extending through its walls adjacent to its lower end, means for connecting said fixed support and said insulating member, a tubular member threaded exteriorly and having the upper end 55 thereof inserted a predetermined distance into the bore of said insulating member, said tubular member having diametrically opposed openings extending through its walls adjacent to the upper end thereof, a pin projected through the openings in the walls of the insulating member and the opening through said tubular member to determine the position of the latter in said bore, a canopy slidably mounted on the tubular supporting member and provided with means for supporting a lighting fixture 60 element, and a nut screwed on the end of the tubular supporting member for determining the position of the canopy relative 65 to the fixed support, said nut being formed with an integral hollow cap portion depending therebelow and arranged to receive the depending end of the threaded tubular supporting member. 70 75

FRANK LOWELL BUTLER.
